US00D991165S

(12) **United States Design Patent** (10) **Patent No.:** **US D991,165 S**
Gong et al. (45) **Date of Patent:** **** Jul. 4, 2023**

(54) **CHARGER**

(71) Applicant: **BEIJING XIAOMI MOBILE SOFTWARE CO., LTD.**, Beijing (CN)

(72) Inventors: **Shengyu Gong**, Beijing (CN); **Xu Wei**, Beijing (CN); **Yin Zhu**, Beijing (CN)

(73) Assignee: **Beijing Xiaomi Mobile Software Co., Ltd.**, Beijing (CN)

(**) Term: **15 Years**

(21) Appl. No.: **35/513,737**

(22) Filed: **Aug. 26, 2021**

(80) **Hague Agreement Data**

Int. Filing Date: **Aug. 26, 2021**

Int. Reg. No.: **DM/216848**

Int. Reg. Date: **Aug. 26, 2021**

Int. Reg. Pub. Date: **Mar. 4, 2022**

(30) **Foreign Application Priority Data**

Mar. 4, 2021 (CN) 202130117616.8

(51) **LOC (14) Cl.** **13-02**

(52) **U.S. Cl.**
